UNITED STATES PATENT OFFICE.

LUTHER E. ROBY AND CLARENCE A. PATTISON, OF PEORIA, ILLINOIS.

RIDING ATTACHMENT FOR HARROWS.

No. 864,337.

Specification of Letters Patent.

Patented Aug. 27, 1907.

Application filed October 16, 1905. Serial No. 283,067.

To all whom it may concern:

Be it known that we, LUTHER E. ROBY and CLARENCE A. PATTISON, citizens of the United States, residing at Peoria, in the county of Peoria and State of Illinois, have invented certain new and useful Improvements in Riding Attachments for Harrows; and we do hereby declare that the following is a full, clear, and exact description of the invention, which will enable others skilled in the art to which it appertains 10 to make and use the same.

This invention has reference to certain new and useful improvements in riding attachments for harrows; one of the objects being to provide a riding attachment which has many advantages from a structural standpoint, in that it is much stronger and more durable to withstand the rough usage to which these articles are necessarily subjected. Furthermore, the attachment can be manufactured at comparatively small cost and is attachable to any ordinary harrow.

20 The riding attachment is constructed with a view of detaching the reach or reaches which are connected with the harrow, from the main frame of such riding attachment and without the use of any tools. Such detachable connections consisting of a suitable key 25 fixedly attached in a suitable manner to the forward end of the main frame, which has a detachable connection with a plate connecting the inner ends of the reaches.

The invention embodies a circle guide attached to 30 the main frame at the rear of the key, aforesaid, which is provided with a suitable depression forming a seat for the inner ends of the reaches which meet at this point, the same serving as a self locking device against undue oscillation of the reaches on their pivot in the 35 forward movement of the harrow, to which the said reaches are connected. And combined with the circle guide we have provided extensions which serve as foot rests and which are adjustably connected with the opposite ends of the circle guide.

40 The general construction of the main frame, which is substantially triangular in shape is made of I beams through the web of which loosely passes the supporting axle, which is loosely journaled in bearings connected with the webs of said I beam. The construction 45 here shown is made with a view of giving the greatest strength with a minimum weight of material, and passing the axle loosely through the said I beams and the bearings thereof, gives a complete freedom between the movement of said frame and the axle 50 in passing over uneven ground.

For a further and full description of the invention herein and the merits thereof, and also to acquire a knowledge of the details of construction of the means for effecting the result, reference is had to the following description and drawings hereto attached.

55 While the essential and characteristic features of

the invention are susceptible of modification, still the preferred embodiment of the invention is illustrated in the accompanying drawings, in which:

Figure 1 is a top plan view of our complete harrow 60 attachment, and in general outline, the plan of a suitable harrow with which the riding attachment is connected; Fig. 2 is a vertical cross-section enlarged, taken on the line x—x of Fig. 1; Fig. 3 is a vertical longitudinal section enlarged, through a portion of 65 the circle guide showing the depression therein and the manner of attaching the same to the I beams. Fig. 4 is a vertical longitudinal section enlarged, taken on the line y—y of Fig. 1; Fig. 5 is an enlarged detail in section showing the adjustable connection between 70 the ends of the circle-guide and the extensions thereof, and Fig. 6 is a detail in cross-section of one of the I beams at the point where the axle passes through the same and the bearings attached thereto.

In the drawings, 1 denotes suitable ground wheels 75 carried upon opposite ends of an axle 2. The axle 2 passes through the rear ends of forwardly carried frame parts 3, which are here shown as I beams, and to the said I beams at a point where the axle passes through the same are attached suitable bearings 80 4. There is no rigid connection between the said frames, the bearings thereof and the axle, as the latter passes loosely through the same, which permits of a freedom of movement of the said frames on their carrying axle. The frames 3 extend forward and parallel 85 each other for a suitable distance and then converge to a central point where they are connected to a plate 5. This said plate overlies a portion of the forward ends of the said frames or I beams 3, as shown, and has the depending plate extensions 6, which extend downwardly and outwardly to the webs of the said beams to which they are suitably secured.

7 denotes a circle-guide which is supported by the frames or I beams 3 at a suitable point to the rear of the plate 5 connecting the same, and is struck on an arc of 90 a circle, the center of which, is the center of a key to be described as attached to the plate 5 with which is detachably connected a plate connected to the inner converging ends of a pair of reaches, which at their outer ends are connected with a harrow. For attaching or 95 connecting the circle-guide to the frames or I beams 3, we employ the plates 8, bolted or otherwise suitably secured to the beams 3 and extending upwardly above the inner edges of the said beams to support the said circle-guide, as shown in Fig. 3, which has a fixed connection with the upper ends of the plate 8 by means of the bolts 9. The central body portion of the circle-guide 7 is depressed as at 10, see Fig. 3, for a purpose to be described.

The foot rests which have been referred to as attached 110 to the circle guide 7 are indicated as 11, and extend out from and beneath the opposite ends of the circle

guide and are slotted as at 12, through which are carried bolts 13 for securing the same to the body of the circle guide 7. Slotting the inner ends of the foot-rests adapts them through the loosening of the bolts 13 to be adjusted 5 in or out for the purpose of lengthening or shortening the same to provide for the difference in height of persons, who may have use for the said riding attachment.

The seat support for the attachment consists of a bar or frame 14, which is secured at its opposite ends to the 10 rear ends of the frames or I beams 3, see Fig. 1, and is elevated a suitable distance for the purpose of securing a seat thereto. As a brace for the said bar 14, we have provided the bar 15 secured at its lower forward end to the center of the circle-guide 7 and extending up- 15 wardly and rearwardly it is secured at its rear end to the bar 14, and at the intersection of the said bars 14 and 15 is suitably secured to the same a seat 16.

Referring again to the plate 5, there is shown, preferably integral therewith but which may be attached 20 thereto a short vertical pin 17 having the forwardly and laterally extended neck portion 18. This pin 17 serves as a king-bolt and also a key to permit the connection and disconnection of parts to be described, as well as permitting such parts to be swung on the said pin.

25 In the drawings, in outline has been shown the plan of one form of harrow which is herein indicated as 19 and having a linked connection therewith is a bar 20, to which is connected a draft attachment 21. The harrow may be of any approved type, and as we do not lay 30 any particular claim to this portion of the machine, it has not been thought necessary to detail the harrow or the parts connected therewith, such for instance, as the draft devices.

22 indicates a pair of reaches, made substantially of 35 angle-iron and secured at their forward ends to the opposite ends of the bar 20, linked to the harrow 19. Said reaches are inclined upwardly and rearwardly converging to a point above the center of the circle-guide 7 and resting in the depression 10 thereof; the inner ends 40 of the said reaches being connected to a block 23 as shown. The said reaches also cross above the forward ends of the frames or beams 3 and at a point coinciding with the plate 5, with which the forward ends of the plates 3 are connected, is provided a plate 24, to which

45 the reaches 22 are secured and the said plate when the parts are in operative position rests upon the plate 5. The plate 24 is provided with an elongated slot 25, which is disposed transversely to the general longitudinal line of draft of the said riding attachment and parts 50 connected therewith. When it is desired to connect the reaches 22 through the plate 24 to the main frame of the attachment, either the main frame or the connecting reaches will be turned at right angles to the other, which will enable the slot 25 of the plate 24 to be passed over 55 the pin 17 and its extension 18, and when the parts are turned into the position shown substantially as seen in Fig. 1, the plates 5 and 24 are locked together with a neck extension 18 of the pin 17 overlying the body of the plate 24, as seen in Fig. 1, and 4. This connection 60 is such that the reaches 22 have a pivotal connection with the frame 3 and adapts their being swung into different positions. The neck of the pin 17 provides for locking the plates 5 and 24 against accidental displacement, and by means of the slot 25 we are enabled 65 to detach the reaches 22 and the harrow by swinging

the said reaches or the main frame into a position where 70 the neck extension 18 and the slot 25 coincide and are parallel one above the other when the reaches 22 with the plate 24 may be raised and very easily disconnected from the said main frame.

Attention is here called to the relation of the inner 75 ends of the reaches 22 with the circle-guide 7 and the connection between the plates 24 and 5, which overlie one another, which maintain a rigid relation to one another relative to any vertical movement, but allow free horizontal movement between the said bars and 80 the main frame. The depression 10 in the circle-guide 7 forms a seat for the inner end of the reaches 22 and prevents undue oscillation of the reaches 22 on the pivot pin 17 in the forward movement of the harrow as the same is dragged over the ground, as in depressing 85 the body of the circle-guide 7, it forms the upwardly curved portions or shoulders 26, which will prevent the inner ends of the reaches riding over the said shoulders unless by some special effort, the said shoulders thereby limiting the swing of the rear end of the reaches through 90 the natural movement of the harrow or its engagement with uneven ground.

Having thus fully described our invention, what we claim and desire to secure by Letters Patent of the United States, is:—

95

1. In a riding attachment of the class described, the combination of a frame consisting of I beams having converging forward portions, bearings attached to the rear ends of the said beams, an axle passing through the said beams and the bearings aforesaid, and ground wheels on 100 the outer ends of said axles.

2. In a riding attachment of the class described, the combination of a frame consisting of I beams, having portions which parallel each other and forwardly extending converging portions, a plate for connecting the forward 105 ends of such beams, bearings attached to the rear ends of the said beams, and an axle passing loosely through the said beams and bearings attached thereto and carrying ground wheels on the outer ends thereof.

3. In a riding attachment of the class described, the combination of a frame consisting of I beams having converging forward portions, bearings attached to the rear ends of the said beams, an axle passing through the said beams and the bearings aforesaid and carrying ground 115 wheels on the outer ends thereof, and a connecting frame adapted to have a pivotal and a detachable connection with the forward ends of said I beams.

4. In a riding attachment of the class described, the combination of a frame consisting of I beams having converging forward portions, a plate for connecting the forward end of said beams, bearings attached to the rear ends of the said beams, an axle passing loosely through the said beams and the bearings aforesaid and carrying ground 120 wheels on the outer ends thereof, and a connecting frame consisting of a pair of reaches which converge from their outer ends to the plate connecting the said I beams and having a pivotal and detachable connection with the said plate.

5. In a riding attachment of the class described, the combination of a frame consisting of a pair of beams supported by an axle and having converging forward portions, a plate for connecting the forward ends of such beams and provided with an upwardly extended pin having a laterally extended neck, a connecting frame composed of a pair 130 of reaches, a plate connecting the said reaches at or near their inner ends and provided with a transverse slot to permit the connection of the said reaches with the beams aforesaid in a detachable and pivotal manner, the said slot of the plate aforesaid when the reaches and beams are in operative connection being disposed at right angles to the 135 neck extension of the said pin.

6. In a riding attachment of the class described, the combination of a pair of beams supported by an axle and

130

135

140

- having converging forward portions, a plate for connecting the forward ends of said beams, a connecting frame consisting of a pair of reaches converging to a point at the rear of said plate, a plate connecting the said reaches, and 5 a key for detachably locking the plate of the reaches to the plate of the frame aforesaid and to adapt them to have a pivotal connection, and a circle-guide attached to the said beams, with which the rear ends of the reaches have a connection.
- 10 7. In a riding attachment of the class described, the combination of a pair of beams supported by an axle, a plate for connecting the forward ends of the said beams, a pair of reaches converging to a point at the rear of the said plate, a plate connecting the said reaches and adapted 15 to overlie the plate of the beams, a key secured to the plate attached to the beams for detachably locking the plate of the reaches with the plate of the beams and to adapt them to have a pivotal connection, a circle-guide attached to the said beams with which the rear ends of the reaches have 20 a suitable connection, and foot-rests extending outwardly from and adjustably connected with the opposite ends of the guide aforesaid.
8. In a riding attachment, the combination of a wheeled frame, a frame consisting of a pair of reaches, a plate attached to the said reaches at or near their inner ends, a key for detachably locking the plate of the reaches to the 25 wheeled frame, and a circle-guide with which the rear ends of the reaches have a connection.
9. In a riding attachment of the class described, the 30 combination of a wheeled frame, a frame consisting of a pair of reaches connected at one end and diverging forwardly therefrom, a plate attached to the said reaches near their connected ends, and a key for detachably locking the plate of the reaches to the wheeled frame and also 35 to adapt the reaches to have a pivotal connection with the said wheeled frame.
10. In a riding attachment of the class described, the combination of a wheeled frame, a frame consisting of a pair of reaches connected at one end and diverging forwardly therefrom, a plate attached to the said reaches near 40 their connected ends, a key for detachably locking the plate of the reaches to the frame aforesaid and to adapt them to have a pivotal connection, and a circle-guide for the connected ends of the said reaches formed with a depression and serving as a seat for the ends of the said reaches.
11. In a riding attachment of the class described, the 45 combination of a wheeled frame, a frame consisting of a pair of reaches connected at one end and diverging forwardly therefrom, a plate attached to the said reaches near
- their connected ends, a key for detachably locking the plate of the reaches to the frame aforesaid and to adapt them to have a pivotal connection, a circle-guide for the connected ends of the said reaches formed with a depression and serving as a seat for the ends of the said reaches.
12. In a riding attachment of the class described, the combination of a frame consisting of I beams having converging forward portions, bearings attached to the rear ends of said beams, an axle passing loosely through the said beams and the bearings aforesaid, ground wheels on the outer ends of said axle, a connecting frame consisting of a pair of angle-iron reaches connected at their inner ends and diverging outwardly therefrom, a plate attached to the said reaches near their connected ends, a key for detachably locking the plate of the reaches to the beams aforesaid and to adapt them to have a pivotal connection, a circle-guide for the connected ends of the reaches and formed with a depression serving as a seat for the ends of the reaches, foot-rests connected to the outer ends of the said guide and a seat support comprising a bar connected at its opposite ends to the rear ends of the I beams, and a brace connected at its forward end to the circle-guide and at its opposite end to the said bar.
13. In a riding attachment of the class described, the combination of a wheeled frame, a pair of reaches connected at one end and diverging forwardly therefrom, means for detachably and pivotably connecting the said reaches to the wheeled frame, a circle-guide for the connected ends of the said reaches attached to the wheeled frame, said circle-guide provided with a central depression and opposite shoulder portions, substantially for the purpose specified.
14. In a riding attachment of the class described, the combination of a wheeled frame, a pair of reaches connected at one end and diverging forwardly therefrom, means for pivotably connecting the reaches to the wheeled frame, a circle-guide for the connected ends of the reaches attached to the wheeled frame, said circle-guide provided with a central depression and opposite shoulder portions, substantially for the purpose specified.

In testimony whereof we affix our signature, in presence of two witnesses.
